UNITED STATES PATENT OFFICE.

JOHN KENNY, OF NEW YORK, N. Y., ASSIGNOR TO JOHN SIMMONS COMPANY, A CORPORATION OF NEW YORK.

INCASED CONCRETE PILING.

1,080,283.

Specification of Letters Patent.

Patented Dec. 2, 1913.

Application filed July 10, 1913. Serial No. 778,268.

To all whom it may concern:

Be it known that I, JOHN KENNY, a citizen of the United States, residing in Brooklyn, county of Kings, city and State of New York, have invented a new and useful Improvement in Incased Concrete Piling, (Case B,) of which the following is a specification.

My invention relates to certain improvements in the construction of the sleeves used, 10 in the construction of reinforced concrete piling, to hold the superposed tubular metallic casing sections in alinement and to guide and hold the internal metallic reinforcing rods in position. One example of such a combination alining and rod-holding sleeve especially adapted for sectional reinforcing rods is shown and described in my prior application for patent filed February 25, 1913, Serial Number 750,498, and allowed June 6, 20 1913.

Among the objects of my present improvement are to lighten the weight of and save metal in combination sleeves of this general description, without impairing their efficiency, and to provide more space between the internal rod-holding tubes for admitting the washing out pipe and for the upward passage through the casing of the earth ejected by the compressed air or water used 30 in washing out.

To these and other ends my invention consists first, in forming short internal rod-holding tubes preferably at one or both ends of the alining sleeve and, secondly, in removing the innermost segments of said rod-holding tubes, substantially as hereinafter described and claimed.

Reference is to be had to the accompanying drawings forming part of this specification in which like parts are designated by the same numbers throughout.

Figure 1 is a longitudinal sectional elevation of a reinforced incased concrete pile embodying my invention. Fig. 2 is an enlarged 45 sectional view of the combination alining and rod-holding sleeve of the same. Fig. 3 is a plan view of the said combination sleeve.

Referring to the drawings, 10, 11, are two tubular metallic sections forming the casing 50 of the pile, 12 is a driving cap preferably used for receiving the blows of the pile driver, 13 is one of the elongated metallic

internal sleeves for holding the abutting 55 ends of the casing sections in alinement, and 16 are reinforcing rods placed and held vertically apart within the pile casing. The concrete or cement filling is poured into the pile casing, after the casing is driven home 60 and the reinforcing rods are placed therein, to bind and unite the casing sections, alining sleeves and reinforcing rods together to form the complete pile. The alining sleeve 15 is in this example of my invention held in 65 position in the abutting end portions of the casing sections by indentations 19 formed in the casing sections above and below the alining sleeve, but may be stopped or positively locked in such position in any other suitable 70 manner.

In my prior application for patent Serial No. 750,498, before referred to, I have shown and described the alining sleeve formed with internal longitudinal tubes for guiding and 75 holding the vertical reinforcing rods in their proper positions in the casing, the construction shown therein being particularly adapted for sectional reinforcing rods. When the continuous or one-piece reinforcing rods 16 80 are used, as shown in Fig. 1, I save weight and metal, and at the same time leave more space for the ejection of earth, stone and rubbish around the compressed air or water pipe used in washing out, by casting sets of 85 short interior rod-holding tubes 17, preferably at each end of the sleeve 15, and omitting the innermost segments of said tubes so as to form segmental openings 18 toward the ends of the casing. By these short inwardly 90 opening tubes 17, the reinforcing rods 16 are equally well guided and held in position apart from the casing wall, while at the same time, the increased space above or below the tubes 17, and the segmental openings 18 as 95 well, leave more room around the washout pipe 20, for the outward passage of the earth etc. around it, as indicated.

By preference, the rod-holding tubes 17, 17^a, hold the reinforcing rods so far apart 100 from the wall of the casing sections 10, 11, that the concrete filling (not shown) will surround the reinforcing rods 16 on all sides, and will thus, as well as the completed pile, be strengthened thereby to the greatest possible extent. 105

I claim as my invention:
The alining sleeve for joining the abutting ends of the metallic casing sections together, formed interiorly with longitudinal guides for holding vertical reinforcing rods, said guides having segmental openings to- ward the axis of the sleeve, substantially as described.

JOHN KENNY.

In presence of—

L. COCHNAR,
PHILLIP WIEGAND.
